United States Patent [19]

Bromley et al.

[11] Patent Number: Des. 297,828

[45] Date of Patent: ** Sep. 27, 1988

[54] FLASHLIGHT BATTERY CHARGER

[75] Inventors: Robert Bromley, Denver, Colo.;
Raymond L. Sharrah, Collegeville,
Pa.

[73] Assignee: Streamlight, Inc., Norristown, Pa.

[**] Term: 14 Years

[21] Appl. No.: 902,387

[22] Filed: Aug. 29, 1986

[52] U.S. Cl. D13/6

[58] Field of Search D13/4-6;
320/2-5; 363/144, 146; 362/183

[57] CLAIM

The ornamental design for a flashlight battery charger,
as shown and described.

DESCRIPTION

FIG. 1 is a front perspective view of a flashlight battery
charger showing our new design;

FIG. 2 is a front elevational view thereof;

FIG. 3 is a rear elevational view thereof;

FIG. 4 is a right end elevational view thereof;

FIG. 5 is a left end elevational view thereof;

FIG. 6 is a right side elevational view thereof;

FIG. 7 is a left side elevational view thereof; and

FIG. 8 is a rear perspective view of a second embodiment
thereof, wherein the only difference resides in the
plug.

The cord is shown broken in FIGS. 1-5 for ease of
illustration.

FIG. 1

FIG. 2
